(57) **CLAIM**

I claim the ornamental design for a pole pruner head, as shown and described.

DESCRIPTION

FIG. 1 is a left perspective view of the pole pruner head; FIG. 2 is a rear view of the pole pruner head shown in FIG. 1;

FIG. 3 is a front view of the pole pruner head shown in FIG. 1;

FIG. 4 is a right side view of the pole pruner head shown in FIG. 1;

FIG. 5 is a left side view of the pole pruner head shown in FIG. 1;

FIG. 6 is a top view of the pole pruner head shown in FIG. 1; and,

FIG. 7 is a bottom view of the pole pruner head shown in FIG. 1.

The subject matter shown in dashed lines, and any surfaces of the design not shown, including interior surfaces, form no part of the claimed invention.
